UNITED STATES PATENT OFFICE.

FRANCIS J. JACKSON, OF ALLEGHENY, PENNSYLVANIA.

WINDOW-CLEANING DEVICE.

No. 863,996.

Specification of Letters Patent.

Patented Aug. 20, 1907.

Application filed April 23, 1907. Serial No. 369,810.

To all whom it may concern:

Be it known that I, FRANCIS J. JACKSON, a citizen of the United States of America, residing at Allegheny, in the county of Allegheny and State of Pennsylvania,

5 have invented certain new and useful Improvements in Window-Cleaning Devices, of which the following is a specification, reference being had thereto to the accompanying drawing.

This invention relates to window cleaning devices, 10 and the invention has for its object to provide a novel device for removing moisture, snow and rain from car windows, the device being particularly designed for street cars whereby a motorman can clean the outside of a platform window and prevent his view from being 15 obstructed.

To this end, I have devised a window cleaning device wherein a scraper is movably mounted upon the outer side of the window frame and adapted to engage the pane of the frame, the scraper being manually moved 20 upwardly and automatically returned to its normal position.

The detail construction entering into my invention will be hereinafter more fully described and then specifically pointed out in the appended claims.

25 Referring to the drawing forming part of this specification, like numerals of reference designate corresponding parts throughout the several views, in which:

Figure 1 is a front elevation of a window frame equipped with my improved device which is illustrated 30 partly in front elevation and partly in section, Fig. 2 is a vertical sectional view of a window frame illustrating the device in elevation, and Fig. 3 is a detail perspective view of a portion of the scraper and an end connection thereof.

35 In the accompanying drawing, I have illustrated a window frame or sash comprising side rails 1, a top rail 2 and a bottom rail 3, said rails holding in position a pane of glass 4. Upon the front of the side rails 1, I secure two vertically disposed tubes 5, said tubes being 40 provided adjacent each end with flanges 6, whereby said tubes can be secured to the frame or sash by screws 7 or similar fastening means. The confronting sides of the tubes 5 are slotted, as at 8, and mounted between said tubes and extending into said slots is a scraper 9 45 having a resilient strip 10, such as rubber engaging the pane of glass 4. The ends of the scraper 9 protrude through the slots 8 into the tubes 5 and are provided with hooks 11, to engage in openings 12 formed in the upper ends of the sleeves 14 right in the tubes 5.

50 The sleeves 14 are suitably connected at their lower ends to elastic cords or cables 15, which pass over

grooved pulleys 16, journaled in the lower ends of the tubes 5. The opposite ends of the elastic cords or cables 15 are suitably fastened in the upper ends of the tubes 5, as at 17.

55 The scraper 9 intermediate its ends is provided with a pierced lug 18 and connected to said lug is a cable or cord 19 which extends upwardly upon the outside of the window pane 4 and passes over a grooved pulley 20 journaled in the housing 21 mounted in the upper rail 60 2 of the frame or sash 1. The end of the cable or cord 19 upon the inside of the window is provided with a ring or suitable grip 22. It will be apparent from the illustration of my invention that I have devised novel means for cleaning the outer side of a window without 65 going outside to accomplish the same. It is obvious that the resilient strip 10 can be easily and quickly renewed at any desired time, and that the device can be made of such a size as to cleanse display windows and windows in dangerous positions, such as the uppermost 70 stories of sky-scrappers or buildings.

The device is preferably constructed of light and durable metal and finished to correspond to or harmonize with the finish of the sash or frame upon which it is mounted.

75 What I claim and desire to secure by Letters Patent, is:—

1. In a window cleaning device, slotted tubes carried by the side rails of a window frame or sash, grooved pulleys journaled in the lower ends of said tubes, a scraper arranged between said tubes and having its ends protruding therein, hooks carried by the inclosed ends of said scraper, sleeves carried by said hooks, elastic cables secured at the upper ends of said tubes and passing downwardly within the tubes and over said grooved pulleys and connected to the said sleeves, a resilient strip carried by said scraper, a grooved pulley journaled in the top of said frame or sash, a cable connected to said scraper and passing upwardly over said grooved pulley to the inner side of said frame or sash, and a ring or grip carried by the end of said cable. 80

2. In a window cleaning device, slotted tubes carried by the side rails of a frame or sash, pulleys journaled in the lower ends of said tubes, a scraper arranged between said tubes, hooks carried by the ends of said scraper within said tubes, elastic cables fastened in the upper ends of said tubes and passing downwardly over said grooved pulleys and connecting with said hooks, a grooved pulley journaled in the top of said sash or frame, and a cable fastened to said scraper and passing upwardly over said grooved pulley to the inner side of said frame or sash. 85

90 In testimony whereof I affix my signature in the presence of two witnesses.

FRANCIS J. JACKSON.
